UNITED STATES PATENT OFFICE.

WILLIAM C. CARPENTER, OF OAKLAND, ILLINOIS.

BELT BUCKLE.

Application filed June 22, 1922. Serial No. 570,156.

To all whom it may concern:

Be it known that WILLIAM C. CARPENTER, citizen of the United States, residing at Oakland, in the county of Coles and State of Illinois, has invented certain new and useful Improvements in Belt Buckles, of which the following is a specification.

My invention relates to improvements in belt buckles.

10 An important object of the invention is to provide a belt buckle having a hook to engage with the belt loop, and a serrated jaw to engage with the flap of the trouser, whereby the buckle is securely held to the 15 trouser against vertical displacement with relation thereto, when in use, but may be readily and conveniently separated from the flap, when desired.

20 A further object of the invention is to provide a device of the above mentioned character, which is of simplified construction and is inexpensive to manufacture.

25 Other objects and advantages of the invention will be apparent during the course of the following description.

In the accompanying drawings, forming a part of this specification, and in which like numerals are employed to designate like parts throughout the same,

30 Fig. 1 is a plan view of a buckle embodying my invention,

Fig. 2 is a central vertical longitudinal section through the same,

Fig. 3 is an end elevation of the buckle,

35 Fig. 4 is a transverse section taken on line 4—4 of Fig. 2,

Fig. 5 is an elevation of the opposite end of the buckle,

Fig. 6 is a bottom plan view of the buckle, 40 and,

Fig. 7 is a plan view of the clamping element.

In the drawings, wherein for the purpose of illustration is shown a preferred embodiment of my invention, the numeral 5 designates a housing, constituting the body portion of the buckle. This housing is U-shaped in cross-section and includes an outer side or top 6 and sides 7. The bottom of the 50 housing is open and is covered by a bottom plate 8, and this plate is provided near corresponding ends with apertured ears 9, for receiving tongues 10, integral with the sides 7. These tongues are bent horizontally over the bottom plate, and hence this 55 end of the bottom plate is locked to the hous-

ing. The bottom plate is provided adjacent to the tongues 10 with a set of inwardly projecting teeth or serrations 11, as shown. The sides 7 are provided adjacent to their opposite ends with apertured knuckles 12, and the end of the plate 8 is slightly reduced and extends between these apertured knuckles. This end of the plate 8 is held against displacement by a pin or pivot element 13, passing through apertured ears 12, as shown.

The numeral 14 designates a jaw extending longitudinally upon the inner side of the bottom plate 8, and this jaw is provided with longitudinal side flanges 15. At one end, these side flanges have apertured knuckles 16 formed therein, receiving the pin 13. The knuckles 16 fit exteriorly of the knuckles 12. The flanges 15 are provided with teeth or serrations 17, as shown. The forward end of the jaw 14 extends inwardly of the serrations 11, as shown.

The jaw 14 is urged toward the bottom plate 8 by a torsional coil spring 18, carried by the pin 13, and having one end engaging the bottom plate 8, and its opposite end engaging the jaw 14, beneath a loop hook or tongue 19. This loop hook or tongue is U-shaped and is preferably stamped from the material of the jaw 14.

One end 20 of the belt is passed into the housing 5 adjacent the bottom plate 8, and is clamped to the bottom plate by means of a transverse cam element 21, pivoted in the 90 housing, and serrated to engage with the end 20 of the belt. The other end 22 of the belt is passed into the opposite end of the housing, adjacent its top 6 and contacts with an inwardly projecting cam 23, preferably 95 formed from a piece of metal integral with the top 6, and bent inwardly from the same. The end 22 of the belt is held against displacement in the adjusted position by means of a double ended sliding clamp 24. This 100 sliding clamp is provided at its end with outwardly extending lateral flanges 26 and 27, facing toward the top 6. The sliding clamp 24 is provided at its edges with fingers 28, projecting through longitudinal 105 slots 29 in the sides 7. The slots 29 are sufficiently wider than the thickness of the fingers 28 to permit of restricted turning movements of these fingers. As shown in Fig. 2, the end 22 of the belt has been inserted 110 within the housing 5 between the cam 26 and the flange 27, and the sliding clamp 24 has

been shifted to the right, so that the flange 27 engages with a portion of the belt beneath and adjacent to the clamp 23. This action forces the flange 27 downwardly and 5 the flange 26 is forced upwardly, to engage with the end of the belt. It is thus seen that the sliding clamping element is made to contact with the belt at two points, and this clamping action increases as the belt is pulled 10 away from the housing 5. It is obvious that the belt may be readily fed into the housing, as the sliding clamp 24 may move away from the cam 23, when desired. To release the end of the belt, the user engages the fingers 28 and shifts the sliding clamp 24 to 15 the left; at which time the end 22 may be withdrawn from the housing.

In the use of the buckle, the same is secured to one end 20 of the belt by means of 20 the clamp or cam 21. The buckle is now brought in proximity to the front flap of the trouser, near the top thereof, and the jaw 14 is arranged upon the inner side of the flap, while the bottom plate 8 and associated elements are arranged upon the outer 25 side of the flap. The teeth 11 and 17 are therefore adapted to securely engage with the fabric of the flap, and the buckle is therefore positively locked to the flap against 30 placement. The hook 19 is also engaged within the belt loop 19'. The free end of the belt is now passed within the housing 5 between the cam 23 and the sliding clamp 24, and adjusted to the desired position, and the 35 clamp will automatically lock the free end of the belt in the desired adjusted position. The free end of the belt may be released by moving the sliding clamp 24, as above stated.

It is to be understood that the form of my 40 invention herewith shown and described is to be taken as a preferred example of the same, and that various changes in the size, shape, and arrangement of parts may be resorted to without departing from the spirit 45 of my invention, or the scope of the subjoined claims.

Having thus described my invention, I claim:

1. A buckle comprising a housing provided 50 in its sides with longitudinal slots and having a cam element near one end, a sliding clamp within the housing provided near its

ends with laterally extending flanges projecting toward the cam, said sliding clamp having fingers slidable within the slots and 55 adapted to partake of restricted turning movements therein, a serrated jaw pivotally connected with one end of the housing and adapted to engage inwardly of the flap of the trousers, and means for securing one 60 end of a belt to the housing while the other end of the belt is adapted to be passed between said cam and sliding clamp.

2. A buckle comprising a body portion, means for securing one end of the belt to the 65 buckle, adjustable means for engaging the opposite end of the belt and secured to the body portion, a serrated jaw extending longitudinally upon the inner side of the body portion and pivotally connected therewith 70 and adapted to engage upon the inner side of the flap of the trousers, and a spring to urge the jaw toward the body portion.

3. A buckle comprising a body portion, means for securing one end of the belt to 75 the body portion, means carried by the body portion to adjustably connect the opposite end of the belt therewith, and a serrated jaw hinged to the body portion and extending longitudinally thereof upon the inner side 80 of the body portion and adapted to engage upon the inner side of the flap of the trousers.

4. A buckle comprising a body portion provided near one end with laterally projecting teeth, means for attaching one end 85 of a belt to the body portion, adjustable means carried by the body portion to engage with the opposite end of the belt, a jaw extending longitudinally upon the inner side 90 of the body portion and hinged to the end thereof opposite the end of the body portion having the teeth, said jaw being provided upon its edges with flanges projecting toward the body portion, said flanges having teeth, a spring to swing the jaw toward the body portion, and a hook carried by the outer side of the jaw and adapted for insertion within the belt loop of the trouser, said 95 jaw being arranged upon the inner side of the flap of the trouser.

In testimony whereof I affix my signature.

WILLIAM C. CARPENTER.
